UNITED STATES PATENT OFFICE.

ISAAC C. DILKS AND JAMES PARK, JR., OF CAVITE, PHILIPPINE ISLANDS.

BOTTLE-CLOSURE.

No. 860,737.

Specification of Letters Patent.

Patented July 23, 1907.

Application filed July 16, 1906. Serial No. 326,487.

To all whom it may concern:

Be it known that we, ISAAC C. DILKS and JAMES PARK, Jr., citizens of the United States, residing at Cavite, Philippine Islands, have invented a new and useful Bottle-Closure, of which the following is a specification.

This invention relates to bottle closures, and has for its principal object to provide means of simple and cheap construction for closing the mouth of a bottle in such manner that it cannot be refilled without detection.

A further object of the invention is to provide a bottle closure in which the neck of the bottle is provided with a weakened portion above which the main closure is located, it being necessary to detach the upper portion of the neck before the contents of the bottle can be poured out.

A still further object of the invention is to provide a device of this type in which provision is made for preventing the passage of any broken glass into the bottle while the neck is being detached.

With these and other objects in view, as will more fully hereinafter appear, the invention consists in certain novel features of construction and arrangement of parts, hereinafter fully described, illustrated in the accompanying drawings, and particularly pointed out in the appended claims, it being understood that various changes in the form, proportions, size and minor details of the structure may be made without departing from the spirit or sacrificing any of the advantages of the invention.

In the accompanying drawings:—Figure 1 is a sectional elevation of the upper portion of the neck of a bottle embodying the invention. Fig. 2 is a sectional plan view of the same on the line 2—2 of Fig. 1.

Similar numerals of reference are employed to indicate corresponding parts throughout the several figures of the drawings.

In carrying out the invention, the bottle 10 is provided with a neck 11, the bore of which is preferably tapered continuously from the top to the base of the neck, although this in all cases is not essential. On the lower portion of the neck is placed a cork 12, which forms a seal for preventing loss of the contents of the bottle by evaporation, and which serves further as a means for preventing the passage of any broken glass into the bottle when the top of the neck is removed. At a point above the top of the cork 12 the neck of the bottle is provided with a weakening groove 15, so that

the top of the neck may be broken off without difficulty, 50 and after the withdrawal of the cork 12 in the usual manner, the contents of the bottle may be poured out.

In order to prevent access to the cork 12, a stopper 17 formed of glass or other suitable material is arranged in the upper portion of the neck, the stopper being 55 preferably provided with a tapered flange 18 at its upper end, said flange fitting over the tapered mouth 19 of the neck, so that it is practically impossible to insert a wire or flexible strip of any material into the neck.

The lower portion of the stopper 18 is provided with 60 a transversely extending opening 20, in which are arranged two pins 21 that are forced apart by a spring 22, the pins seating in notches or grooves 23 formed in the inner wall of the neck.

After the bottle has been filled, the cork 12 is driven 65 down into position, and then the stopper 17 is inserted, the inclined wall 19 of the mouth serving as a means for gradually forcing the pins 21 inward against the stress of the spring 22, and the tapered bore of the bottle neck further assisting in this operation, so that the stopper 70 may be readily placed in position and forced downward until the pins 21 spring out into the recesses 23. The stopper is thus permanently locked in the upper portion of the neck and cannot be removed until the neck is broken into fragments.

75

It will be noted that the glass stopper occupies the portion of the neck above the weakening groove with its lower surface approximately in alignment with the upper wall of said groove, whereby when the top of the neck is broken off the stopper as a whole is detached and 80 may be removed from the detached portion of the neck for subsequent use. Also, the sealing cork 12 is located wholly below the plane of the weakening groove with its upper surface slightly below the lower wall of said groove to permit of the entire removal of the reduced 85 portion of the neck from that part of the neck which remains on the bottle after the top has been detached. It will be noted that the stopper and sealing cork, respectively, constitute reinforcements at opposite sides of the weakening groove and thus serve to confine the 90 cleavage to the grooved portion of the neck.

We claim:—

In a bottle, a neck having continuously tapered bore of gradually increasing diameter from the body of the bottle outward, the mouth portion of the neck being provided 95 with a tapered stopper receiving seat, and the peripheral portion of said neck being provided with a weakening groove, a cork seated in the tapered lower portion of the neck and having its upper face slightly below the lower-

most wall of the weakening groove, a stopper inserted in the mouth portion of the neck and having a tapered flange that seats against the tapered seat, the lower face of the stopper being approximately in alinement with the upper 5 wall of the weakening groove, so that both the stopper and cork form reinforcements at the opposite sides of such groove and tend to confine the cleavage to the grooved portion of the neck, and means for locking the stopper in place.

10 In testimony that we claim the foregoing as our own, we

have hereto affixed our signatures in the presence of two witnesses.
